UNITED STATES PATENT OFFICE.

ROGER TULL, OF LOS ANGELES, CALIFORNIA, ASSIGNOR TO WESTERN LITHOGRAPH COMPANY, OF LOS ANGELES, CALIFORNIA, A CORPORATION OF CALIFORNIA.

METHOD OF MAKING CLOTH STENCILS.

Application filed June 28, 1926. Serial No. 119,040.

This invention relates to methods of making cloth stencils and, more especially, the type of stencil employing bolting cloth through which paint is forced onto a sheet 5 of paper or other surface that is to receive the design.

An object of the invention is to lessen the expense of making stencils of this character.

A further object is to eliminate some of 10 the free-hand drawing that heretofore has been necessary in the preparation of stencils of this type.

A still further object is to enable the production of very small lettering and fine 15 detail work in designs, this being heretofore impossible of achievement with oil paint processes.

It is at present customary in the photographic method of making cloth stencils, 20 through which paint is forced, for the artist to make a black and white drawing for each color of paint that is to be employed, the drawings prepared by the artist being different and each drawing showing only 25 those portions that are to be printed in a particular color. These drawings are made upon transparent sheets of paper laid over the colored original. Thus, there is involved a considerable amount of costly hand work. 30 The drawings thus made are then photographed.

Another common method at present in use is for the artist to block out each stencil cloth screen by hand from the original 35 sketch. This, of course, also involves a considerable amount of costly hand work.

By this new method, when the negative is made by hand, the artist need only prepare one such negative on a sheet of transparent celluloid, or similar substance, which is laid upon the colored original, and the artist with a brush and suitable opaque paint copies upon the transparent celluloid, the original drawing. The celluloid drawing, which actually constitutes a negative, 45 thus made, is simply a silhouette or flat tone line drawing. The photographic method of preparing the negative is accomplished by the usual photographic process, the colored original being photographed on a sensitized plate, the exposed plate developed, and said plate then fixed. It is the artist's work that is so expensive in the preparation of stencils of this character and

the more of this work that can be eliminated, 55 the cheaper the stencils can be made.

Other objects and advantages will appear in the subjoined detailed description.

The accompanying drawings illustrate the results of certain operations of the method 60 embodying the invention:

Figure 1 represents the colored original which is to be reproduced.

Figure 2 represents one of the negatives made by copying the colored original. A 65 printed transparency is also shown applied to the negative.

Figure 3 represents the printed transparency shown applied in place on the negative in Figure 2. 70

Figure 4 represents a print made photographically on bolting cloth from the negative in Figure 2.

Figure 5 represents a screen produced by 75 the artist blocking out with lacquer the portions of the print shown in Figure 4 that are to be impervious to the paint.

Figure 6 represents another screen made in the same manner as that shown in Figure 5 by the use of another such print as shown 80 in Figure 4.

Figure 7 represents the result of forcing paint through the screen shown in Figure 5 upon paper or other suitable material.

Figure 8 represents the result of forcing 85 paint through the screen shown in Figure 6, upon paper or other material already printed in one color, as shown in Figure 6.

It will be readily understood that the different views mentioned above do not perfectly represent the results of the various operations because of the limitations imposed by representing wash drawings with line drawings. The drawings are only approximations of the results secured by various operations, and the different colors in the colored original are indicated by lines extending in different directions. 95

In order to perform the method, a drawing or print is used and the same preferably appears in the colors that are to be reproduced and such drawing or print is herein termed "colored original". The original in color is represented in Figure 1 of the drawings and in this instance, for example, the horizontal lines indicate the color blue, the vertical lines indicate the color red, and the combination of vertical and

horizontal lines indicates gray or black. The colored original may be in solid colors or may be a line drawing. A negative, as indicated in Figure 2, is made from the colored original and this negative may be made either by hand or photographically and, in either event, the negative will be made on a transparent plate.

For example, when the negative is to be made by hand, a sheet of transparent celluloid or similar transparent substance is laid upon the colored original and the artist with brush and a suitable opaque paint copies upon the transparent plate the colored drawing therebeneath. The drawing thus made is simply a silhouette or flat tone drawing.

When the negative is made by the usual photographic process, the colored original is photographed on a sensitized transparent plate, the exposed plate developed and then fixed.

After the negative is prepared as described above, a plurality of photographic prints are made on light-sensitized bolting cloth from said negative, one for each color of the original drawing or each color that is to be reproduced. In the instance illustrated, to reproduce the colored original shown in Figure 1, it would be necessary to make three prints from the negative, one for the blue color, one for the red color, and one for the black or gray. One such print is represented in Figure 4 and it will be readily understood that the others are simply duplicates of the one represented.

The photographic prints mentioned above may be made as follows: No. 14XX bolting cloth is stretched over the edge of a wooden frame and the cloth thus stretched is taken to a dark room, and a camel hair brush is employed for covering the bolting cloth on the outer side with a solution made as follows: 90 grains of bichromate of ammonia is dissolved in 5 ounces of distilled water and this mixture will be identified as mixture A. 2 ounces of liquid glue are mixed with the white of one egg or albumen egg Merck, and this will be identified as mixture B. Mixtures A and B thus produced will then be thoroughly stirred together and 10 drops of aqua ammonia added and this mixture will be identified as mixture C. Metal must not touch the solution nor should it be exposed to any except red light. After the sensitizer thus made has been applied to the bolting cloth and has dried, the drying taking about an hour, the sensitized cloth is ready for printing from the negative.

For printing, the negative will be placed in close contact with the sensitized bolting cloth and then exposed, say for 5 minutes in front of two 500 watt lamps. After thus exposing, the negative is removed and the bolting cloth thus exposed is washed under running water to wash out the glue solution printed on a strip 9, shown in Figure 3, of

Compressed air will be used to free the clear portions of the bolting cloth of the water. Those portions of the sensitizer rendered insoluble in water by the action of light will not be washed off.

After this treatment, the printed bolting cloth will be placed in the sunlight until the sensitizer that remains hardens. This takes about 10 minutes. If there is no sunlight, it should dry in a place free from dust.

The artist next blocks out with lacquer upon each of the bolting cloth prints those portions that are to be impervious to the paint employed in making the particular color run with the screen thus produced. The resulting screens are indicated in Figures 5 and 6, the one in Figure 5 being for the red color run and the one in Figure 6 being for the blue color run. The screen for the black or gray reproduction is not illustrated, since it will be readily understood that in preparing such screen, the artist will block out with lacquer all portions that are not to appear in black or gray, leaving all portions blank or clear that are eventually to appear in the reproduction in black or gray. In blocking out, the artist has followed out this procedure in making the screens shown in Figures 5 and 6, as in the screen illustrated in Figure 5, he has blocked out only those portions that are eventually to appear in blue and blank, leaving blank the portions that are to appear in red. Also in Figure 6, he has blocked out only those portions that are to appear in red and black, leaving blank or clear those portions that are to appear in blue. Thus, the screens shown in Figures 5 and 6 are exactly the reverse of one another.

After the screens have been prepared in this manner, they will be treated with lacquer mixed with No. 206 Zapon blue and No. 16 Zapon thinner, or other suitable nitro-cellulose products. This solution is applied on one side of the screen with a large brush and, at the same time, the other side of said screen is rubbed with a soft rag.

The stencil screens are now ready for use in a manner well understood in the art relating to the printing of cloth stencils of this character. Briefly, paper or cardboard will be placed beneath the stencil screens and paint will be forced through said stencil screens by application of a squeegee to the back of the screen, the screens being used successively to make the color runs in rotation.

In order to reproduce relatively small letters, such as form, for example, the words "Radio tube", as indicated in the drawings, it is preferable to perform the following operations: The negative indicated in Figure 2, if made by the artist, will omit the fine lettering "Radio tube" and said words will be printed on a strip 9, shown in Figure 3, of

celluloid or equivalent thin transparent substance and said printed strip will then be secured by a transparent glue or adhesive on the negative in the position that it is desired the lettering is to appear in the final 5 reproductions. The strip 9 is shown in place in Figure 2. Obviously, the print indicated in Figure 4 and the screens indicated in Figures 5 and 6 will contain the words shown 10 on the strip 9, since the light rays will be obstructed by the letters printed on said strip.

In many instances, it is of advantage, especially when there is small detail in the 15 design, to allow a color to overlie a portion of another color, and, consequently, in such event some portions of the screen may be left open even though such open portions correspond in position with the colors that 20 are afterward to be forced through a different screen.

I claim:

1. The method of making stencils consisting in making a negative from the colored original that is to be reproduced, making a plurality of photographic prints on sensitized bolting cloth from said negative, and blocking out on the several prints the 25 portions that are to be impervious to paint and that correspond respectively to the different colors.

2. The method of making stencils consisting in making a photographic negative from the colored original that is to be reproduced, 30 making a plurality of photographic prints on sensitized bolting cloth from said negative, and blocking out on the several prints the portions that are to be impervious to paint and that correspond respectively to the different colors.

3. The method of making stencils consisting in laying a transparent plate over the colored original that is to be reproduced, copying in opaque paint upon the plate the 45 colored original, making a plurality of photographic prints on sensitized bolting cloth from the painted plate, and blocking out on the several prints the portions that are to be impervious to paint and that correspond respectively to the different colors.

4. The method of making stencils consisting in making a negative from the colored original that is to be reproduced, printing upon a transparent strip some of the lettering it may be desired to have appear in the reproductions, securing the printed strip upon the negative, making a plurality of photographic prints on sensitized bolting cloth from the negative after the printed 55 strip has been affixed thereto, and blocking out on the several prints the portions that are to be impervious to paint and that correspond respectively to the different colors.

5. The method of making stencils consisting in making a negative from the colored 60 original that is to be reproduced, printing upon a transparent strip details not present in said original, securing the printed strip upon the negative, making a plurality of photographic prints on sensitized bolting 65 cloth from the negative after the printed strip has been affixed thereto and blocking out on the several prints the portions that are to be impervious to paint and that correspond respectively to the different colors. 70

6. The method of making stencils consisting in making a negative from the colored original that is to be reproduced, making a plurality of photographic prints on sensitized bolting cloth from said negative, and 75 blocking out on the several prints the portions that are to be impervious to paint.

7. The method of making stencils consisting in making a photographic negative from the colored original that is to be reproduced, 80 making a plurality of photographic prints on sensitized bolting cloth from said negative, and blocking out on the several prints the portions that are to be impervious to paint. 85

8. The method of making stencils consisting in laying a transparent plate over the colored original that is to be reproduced, copying in opaque paint upon the plate the 90 colored original, making a plurality of photographic prints on sensitized bolting cloth from the painted plate, and blocking out on the several prints the portions that are to be impervious to paint. 95

9. The method of making stencils consisting in making a negative from the colored original that is to be reproduced, printing upon a transparent strip some of the lettering it may be desired to have appear in the reproductions, securing the printed strip upon the negative, making a plurality of photographic prints on sensitized bolting cloth from the negative after the printed strip has been affixed thereto, and blocking out on the several prints the portions that are to be impervious to paint. 100

10. The method of making stencils consisting in making a negative from the colored original that is to be reproduced, printing upon a transparent strip details not present in said original, securing the printed strip upon the negative, making a plurality of photographic prints on sensitized bolting cloth from the negative after the printed strip has been affixed thereto, and blocking out on the several prints the portions that are to be impervious to paint. 110
